UNITED STATES PATENT OFFICE

2,569,901

SYRINGE FOR REGIONAL ANESTHESIA OF
THE LOWER JAW

Ernest Nicolas Richard, Lille, France

Application July 17, 1947, Serial No. 761,482
In France June 17, 1946Section 1, Public Law 690, August 8, 1946
Patent expires June 17, 1966

5 Claims. (Cl. 128—215)

1

The regional anaesthesia of the lower jaw at Spix's spine presents such difficulties that it is only very rarely practised, notwithstanding the advantages that it presents both for the patient and for the surgeon or dentist. If it is effected with an ordinary syringe provided with the usual needle, the traumatism and post-operational pains are hard for the patient to bear, and furthermore breakages of needles are to be feared.

The present invention relates to improvements in syringes for the anaesthesia of the lower jaw at Spix's spine, and is characterised by the arrangement, on the ferrule carrying the needle, of a cursor, the position of which is adjustable, surrounding the needle over a certain length, and prolonged by a support carrying a ring designed on the one hand to limit the penetration of the needle and on the other hand to resist any excessive bending of the needle.

One embodiment of the invention is diagrammatically illustrated by way of example but not of limitation in the accompanying drawings, in which:

Figure 1 shows a syringe according to the invention in axial section;

Figure 2 is a profile view of the body of the syringe; and

Figure 3 is a diagram showing the curvature that may be assumed by the needle.

In these drawings, A is the barrel of the syringe, which may be of metal, glass or other material, and which is provided with suitable finger bars or handles b and c. It contains a piston d, equipped with a ring e. The two handles are held by a split collar f, maintained on the body by hooks or clasps g, g', and connected by longitudinal strips h, h' to a sleeve i. This sleeve comprises a screw-threaded part for securely holding a ferrule K by means of a nut j.

The ferrule K comprises at one end a collar or flange upon which the nut j bears for the purpose of fixing the ferrule to the frusto-conical ground-in nozzle of the syringe barrel, and at the other end a screw-thread on to which is screwed a coupling tube m for securing the needle l. This coupling tube m has a screw-threaded extension along which can be screwed a cursor sleeve n, which surrounds the needle over a certain length. The needle l is very fine, and is of a length of about fifty millimetres. It is constructed like the needles used for local anaesthesia.

Parallel to the bottom of the cursor sleeve n through which the needle passes, and about five millimetres beyond this bottom, is arranged a

2

ring o, which is carried by a stem q, which forms an extension of the cursor n. The cursor is locked in position by a lock-nut p. The stem or shank q enables the orientation of the bevel r of the needle to be marked. The ring o limits the penetration of the needle into the flesh, resists any excessive deflection of the needle and converts the acute angled bend which might otherwise occur at the point s (Figure 3), and which would involve the risk of breakage of the needle, into an open curve no longer involving any danger.

Furthermore, as a result of this arrangement of the ring o, in the event of the needle being broken by unskilful manipulation at the point where it leaves the cursor n, there would remain outside the flesh a portion of the needle enabling it to be taken hold of and easily withdrawn.

A syringe has thus been provided which obviates all risk of the ferrule K falling off in the course of an operation, and enables long and very fine needles to be utilised with full security.

I claim:

1. A syringe for the anaesthesia of the lower jaw at Spix's spine, comprising: a barrel, a nozzle at the outer end of the barrel, a ferrule engaging the outer end of the nozzle, a hollow needle carried by the ferrule, a cursor adjustable on the ferrule and surrounding the needle over part of its length, a rigid support constituting an integral extension of the cursor, and a rigid ring in a plane perpendicular to the axis of the syringe, integral with the support and encircling the needle, this ring being adapted to limit the penetration of the needle and to prevent excessive bending of the needle.

2. A syringe for the anaesthesia of the lower jaw at Spix's spine, comprising: a barrel, a nozzle at the outer end of the barrel, a ferrule engaging the outer end of the nozzle, a hollow needle carried by the ferrule, a cursor adjustable on the ferrule and surrounding the needle over part of its length, a lock-nut for locking the cursor in its adjusted position, a rigid support constituting an integral extension of the cursor, and a rigid ring integral with the support and encircling the needle, this ring being adapted to limit the penetration of the needle and to prevent excessive bending of the needle.

3. A syringe for the anaesthesia of the lower jaw at Spix's spine, comprising: a barrel, a nozzle at the outer end of the barrel, a ferrule engaging the outer end of the nozzle, a hollow needle carried by the ferrule, the needle having a beveled point, a cursor adjustable on the ferrule and

surrounding the needle over part of its length, a rigid support constituting an integral extension of the cursor, the support being formed with a gap so positioned as to enable any deflection of the needle to be observed, and a rigid ring co-axial with the syringe barrel and integral with the support and encircling the needle, this ring being adapted to limit the penetration of the needle and to prevent excessive bending of the needle.

4. A syringe for the anaesthesia of the lower jaw at Spix's spine, comprising: a barrel, a nozzle at the outer end of the barrel, a ferrule engaging the outer end of the nozzle, a hollow needle carried by the ferrule, the needle having a beveled point, a cursor adjustable on the ferrule and surrounding the needle over part of its length, a rigid support constituting an integral extension of the cursor, the support consisting of a single shank located parallel to the axis of the cursor and in a predetermined angular relationship to the bevel at the point of the needle, so as to enable the position of the bevel to be ascertained by inspecting the said shank, and a rigid ring integral with the support and encircling the needle, the plane of the ring being parallel to the bottom of the cursor this ring being adapted to limit the penetration of the needle and to prevent excessive bending of the needle.

5. A syringe for the anaesthesia of the lower jaw at Spix's spine, comprising: a barrel, a nozzle

at the outer end of the barrel, a ferrule engaging the outer end of the nozzle, a hollow needle carried by the ferrule, a cursor adjustable on the ferrule and surrounding the needle over part of its length, a rigid support permanently unitary with the cursor, and a rigid ring permanently unitary with the said support and encircling the needle, the barrel, the nozzle, the ferrule, the cursor and the ring being co-axial with one another, and the ring being adapted to limit the penetration of the needle and to prevent excessive bending of the needle.
